UNITED STATES PATENT OFFICE.

NINKO SPANOVIC, OF DUQUESNE, PENNSYLVANIA.

WRENCH.

Application filed September 30, 1924. Serial No. 740,831.

To all whom it may concern:

Be it known that I, NINKO SPANOVIC, a citizen of the United States of America, residing at Duquesne, in the county of Allegheny and State of Pennsylvania, have invented certain new and useful Improvements in Wrenches, of which the following is a specification.

My present invention relates generally to wrenches and more particularly to adjustable wrenches, my object being the provision of a wrench of the type generally known as monkey-wrenches, which will be strong, durable and effective and which includes parallel clamping members or jaw supporting members and opposing jaws carried by said members, together with a handle to which the said clamping members are pivoted adjacent to one end and in laterally spaced relation whereby the jaws will automatically tighten when the wrench is applied in use.

In the accompanying drawing which illustrates my present invention and forms a part of this specification,

Figure 1 is a side elevation;

Fig. 2 is a similar view, partly broken away in order to illustrate the effective position of the spring; and

Fig. 3 is a detail perspective view of the spring removed.

Referring now to these figures my present invention proposes a wrench wherein the rigid jaw 10 is in the form of an angular extension upon one end of a clamping member or jaw supporting shank 11, the adjustable jaw 12 being carried by a frame 13 which is slidable at one side on the shank 11 and which frame has an inner extension 14 spaced from its jaw 12, the latter of which thus opposes the rigid jaw 10. In the space between the movable jaw 12 and the extension 14 of the frame of this jaw is a milled rotatable sleeve 15 internally threaded to engage the threads of the screw shank 16 of the movable jaw, the latter of which projects through an opening in the extension 14 of the movable jaw frame and is provided at its inner end with a head 17 disposed in laterally spaced alined relation with the inner end of the shank 11 as particularly seen in Fig. 2.

The outer end of screw shank 16 thus projects into the adjusting sleeve 15 to an extent variable according to the position of the movable jaw relative to the fixed jaw, the outer end of the adjusting sleeve rotating

around the projecting head of a guide screw 15^a which is threaded as particularly shown in Figure 2 into the movable jaw.

Moreover as particularly seen in Fig. 2 the head 17 of the screw shank and the adjacent inner end of the shank 11 are disposed within the slotted outer end of the handle 18, the slot of which is at 19. In this slot the head 17 and the inner end of the shank 11 are movably held by transverse pivot pins 20 and 21 and the inner squared ends of the head 17 and shank 11 are engaged by the outer flat portion 22 of a controlling spring whose ends are turned inwardly in spaced relation to the outer flat portion 22 and terminate in adjacent angular extensions 23 the latter of which are seated in an axial cavity 24 of the handle centrally of the base of its slot 19.

In this way the spring will be held seated within the base of the slot and the inner squared portions of the head 17 and shank 11 will by virtue of such engagement of the spring serve to clearly hold the two shanks 11 and 16 in parallel outstanding relation, both shanks being, however, free to yield in a slightly angular direction when the wrench is applied in use in order that when the handle 18 is grasped, the two jaws will automatically shift toward one another.

This it will be obvious takes place without prejudice to ready adjustment of the movable jaw by rotation of the milled sleeve 15 in one direction or the other depending upon whether the jaws are to be shifted toward or away from one another and it becomes quite apparent from this that the wrench as a whole is capable of ready, quick and convenient manipulation, will be especially effective and efficient in use, and is of a strong durable nature.

I claim:

1. A wrench comprising a pair of opposing jaws, jaw supporting members therefor disposed in parallel relation, of which the jaw of one supporting member is adjustable with respect thereto for adjustment toward and away from the other jaw, and a handle having a slot at one end in which the inner ends of the said jaw supporting members are pivotally mounted in laterally spaced and alined relation, the handle having a cavity centrally of the base of the slot, and a spring having side portions bent upon themselves and similarly engaging the inner ends of the two jaw supporting members, said spring

being disposed in the slot of the handle and having inturned ends terminating in angular extensions between the said side portions seated in the said cavity.

5. 2. A wrench consisting of a rigid shank having an angular jaw at its outer end, a movable jaw opposing the rigid jaw, a frame in connection with which said movable jaw is formed, slidably supported on the rigid 10 shank and having an extension spaced from the movable jaw, an internally threaded and externally nurled sleeve in said space, a supporting screw entering the movable jaw and arranged with its head within, and 15 forming a bearing for, the outer end of said

sleeve, a screw shank having its outer end movable through said extension and into the inner end of the said nurled adjusting sleeve, said screw shank being provided with a head at its inner end, a handle having a slot at one end in which the adjacent ends of the rigid shank and the screw shank are pivoted in laterally alined and spaced relation, and a spring in the slot of the handle engaging the inner ends of 20 said shanks for the purpose set forth. 25

In testimony whereof I have affixed my signature.

NINKO SPANOVIC.
